BATTERY TERMINAL CLAMP

Austin G. Goodnight, Laton, Calif.

Application June 8, 1946, Serial No. 675,448

1 Claim: (Cl. 173—259)

1

This invention relates to clamping devices and more particularly to battery connectors or terminals.

The difficulties inherent to present known battery connectors are well known. They are unwieldy. When connected for a period of time, they frequently have to be broken to be disengaged from the battery. The manipulation of a wrench in the limited space in which batteries are usually positioned, to tighten or loosen conventional clamps, is inconvenient. Vibration and wear results in faulty electrical transmission. Faulty transmission induces increased corrosion which continues the vicious circle and further aggravates the above mentioned difficulties.

An object of my invention is, therefore, to provide an electrical connecting device conveniently and easily manipulated.

Another object of my invention is to provide a connecting device adapted to exert a substantially uninterrupted clamping pressure independent of battery post wear, vibration, or other deleterious effects encountered during operation.

Another object is to provide an electrical connector distendable for connecting purposes by the application of tension thereto and providing dependable electrical connection to terminals circumscribed thereby upon the release of said tension.

Another object is to provide a battery connector minimizing corrosion by providing constant, or increasingly efficient, electrical transmission during operation.

A further object is to reduce damage to battery posts and batteries incident to present known connectors.

A still further object is to provide battery connectors having clamping surfaces adapted to produce efficient electrical conduction and facile and dependable positioning and to provide improved elements and arrangements thereof in a device of the character and for the purposes set forth.

In accomplishing these and other objects of the present invention, I have provided improved details of structure, the preferred forms of which are illustrated in the accompanying drawing, wherein:

Fig. 1 is a perspective view of one form of the device of the present invention. The further figures show, in elevational view, portions of the present invention having clamping surfaces of specialized configuration as viewed from an

2

imaginary plane passed between the portions of the connector and through guides for said portions, presently more fully described.

Fig. 2 is an elevational view of such a portion of the battery connector showing a clamping surface comprised of pyramidal engaging teeth.

Fig. 3 shows a similar portion in elevation having a frusto-conical clamping surface to engage frusto-conical battery posts.

Fig. 4 illustrates a clamping surface having longitudinal corrugations.

Fig. 5 shows a clamping surface having inwardly disposed longitudinally elongated teeth.

Fig. 6 illustrates a clamping surface providing a waffle grid clamping surface.

Referring more in detail to the drawing:

In Fig. 1 a battery connector of the present invention is indicated. Said connector comprises a gripping member 10 generally annular in its internal surface, being severed to form a pair of cooperatively employed substantially arcuate portions or gripping elements; a base portion 11 and an end portion 12 respectively; bounding an opening 13 provided to receive battery posts. The annular or arcuate character need not be strictly adhered to. The peripheries of the portions are shaped in response to convenience and strength required. Further, said connector may be severed to form any number of gripping elements in response to particular connecting problems confronted.

The base portion 11 of the battery connector is provided with a receptacle 14 to which is secured, as by soldering, an electrical conductor, such as the wire 15 shown in light line construction in Fig. 1.

A handle 16 is provided on the end portion 12 of the battery connector by which tension is applied to the said connector when it is desired to distend the respective portions thereof and enlarge the opening 13 to encompass a battery post with which electrical communication is desired.

Substantially parallel bores 17 are formed in the end portion 12 in a plane common to both portions of said connector when said portions are in operating position and of a direction in said plane to coincide with desired direction of relative movement of said portions. This is preferably longitudinally to the gripping member 10.

Guides 18 are secured in the bores 17 as by means of locking pins 19 and disposed to engage the base portion 11 of the connector.

Bores 20 are formed in said base portion 11 aligned with the bores 17 of the end portion 12 and of a size to receive the guides 18. Said guides are slidably engaged within the bores 20.

Elongated access openings 21 are provided in the base portion 11 of the connector into which the guides 18 extend from one end. To maintain the battery connector in contracted position and to exert a continuous force tending to draw the portions 11 and 12 together, resilient means, such as helical springs 22 are provided. The springs are positioned circumjacent the guides 18 in an abutting relation to the base portion 11 at the ends of the access openings from which the guides enter said openings. Pins 23 are passed through the ends of the guides extending into the openings 21 and serve as spring retainers and guide stops; when joined by the guides 18, the portions 11 and 12 of the connector may be manually distended, or constricted by the spring action, as desired, within the limits to which they are constrained by said guides.

In Fig. 1, a plurality of teeth 24, positioned transversely to the clamping surface, are shown inwardly disposed to the battery post opening 13. The said teeth have apices 25 at their extremities, adapted to embrace battery posts to which electrical connection is desired.

A modified form of gripping surface shown in Fig. 2 comprises teeth 26, similar to the teeth 24 but sharpened into pyramidal form to reduce area of contact with said battery terminals and increase the biting effect. This modified gripping surface and other modifications presently described circumscribe the battery post opening 13.

In Fig. 3 a frusto-conical gripping surface 27 is provided. When battery posts of soft material are to be engaged, the gripping surface 27 serves to reduce wear thereon by spreading the constrictive force exerted by the connector over a wider area of conventional frusto-conical battery posts. Said gripping surface 27 is generally somewhat more easily released from engagement than is any of the other gripping surfaces shown because of the absence of biting action.

Longitudinal corrugations 28 illustrated in Fig. 4 are positioned to bear a circumscribing relation to engaged battery posts and thus to resist movement of the connector longitudinally of said post. It is to be noted that a wearing of the said battery post engaged serves to seat the corrugations and provide increasingly effective electrical contact. It is further to be noted that even a small amount of wear serves to seat a greatly increased area of the gripping surface in contrast to a substantially constant and slower increase in seating area due to wear whenever the gripping surfaces shown in Figs. 1, 2, 5, or 6 are employed.

Longitudinally elongated teeth 29, indicated in Fig. 5, also resist movement of the connector longitudinally of the battery post during operation. The elongated teeth provide sharp engaging means and are well adapted to battery posts of hard material. Said teeth 29 provide a biting action on battery posts engaged.

In Fig. 6, a gripping surface having a waffle grid clamping surface 30 is illustrated. The waffle grid, providing edges transversely and longitudinally disposed to an engaged battery post, is well suited to resist vertical, horizontal and rotational movement thereon. The gripping areas of the grid 29 may be optionally provided with indentations 31 therein.

I have shown clamping surfaces having battery

post engaging projections positioned transversely and longitudinally to the clamping surfaces and clamping surfaces having no projections. These specialized configurations illustrate preferred embodiments of clamping surfaces which may be further modified or combined as individual needs suggest.

Operation

10 The operation of a battery connector constructed as described is as follows:

By gripping the base portion 11 of the connector and the handle 16, tension is applied to the said connector sufficient to overcome the influence of the springs 22 and distend the connector. While distended, the connector is positioned on a battery post (not shown) with which electrical communication is to be established. The tension is then released permitting the base portion 11 and end portion 12 to be drawn in to electrical contact and clamping relation with the battery post by the springs 22.

When clamping surfaces of reduced area such as those illustrated in Figures 1, 2, 4, 5, and 6 are employed, the continual inwardly directed pressure serves to maintain electrical contact in spite of wearing of the terminal. The bite action of the teeth actually increases the conductivity of the connection when wear occurs because of the improved seating that results.

The battery connector of the present invention resists any tendency to loosening incident to vibration. The resilient means 22 permits a limited relative movement of the connector and battery post yet always maintains firm engagement and electrical communication. This constant maintaining of efficient electrical contact also serves to reduce corrosion of the post and connector. Further, the teeth 24, 26 and 29, the corrugations 28, and the waffle grid 30 provide air passages adjacent points of electrical contact that tend to inhibit corrosion.

To remove the connector from the battery post, tension is again applied to distend the connector which is then merely lifted from battery post engagement.

It is obvious that I have provided an electrical connector adapted to exert a substantially uninterrupted clamping pressure in spite of vibration and wear of the battery post and connector, being conveniently and easily manipulated and reducing corrosion and damage to batteries incident to conventional battery connectors.

Although I have herein shown and described my invention in what I have conceived to be the most practical and preferred embodiments, it is recognized that departures may be made therefrom within the scope of my invention, which is not to be limited to the details disclosed herein, but is to be accorded the full scope of the claim so as to embrace any and all equivalent devices and systems.

Having described my invention, what I claim is new and desire to secure by Letters Patent is:

65 A battery terminal connector comprising a pair of cooperative elements having adjacent inner ends, oppositely disposed outer ends, and opposite side edges, the adjacent inner ends defining an opening adapted to receive a battery post, one of 70 said elements being formed with a bore inwardly from an outer end thereof adapted to receive a battery cable; a pair of parallel guides rigidly mounted in one of the elements and endwardly extended from the inner end of said element on opposite sides of the post receiving opening, the

opposite element having bores formed inwardly from the inner end thereof on opposite sides of the post receiving opening slidably receiving the guides and being formed with an enlarged access opening along each bore open to a respectively adjacent side edge of said element, the access openings having inner ends defined by portions of the element circumscribing the bores adjacent to the inner end of said element, a helical spring mounted on each of the guides within the guide's respective access opening, and spring retainers mounted on the extended ends of the guides within the access openings maintaining the springs under compression between said retainers and the inner ends of the access openings.
